(57) **CLAIM**

The ornamental design for an armature cam, as shown and described.

DESCRIPTION

FIG. 1 is a front view of an armature cam, according to the present invention;

FIG. 2 is a rear elevation view thereof;

FIG. 3 is a right-side elevation view thereof;

FIG. 4 is a left side elevation view thereof;

FIG. 5 is a bottom plan view thereof;

FIG. 6 is a top plan view thereof;

FIG. 7 is a top-front-left side perspective view thereof;

FIG. 8 is a top-rear-right side perspective view thereof; and,

FIG. 9 is a bottom-front-right side perspective view thereof. The broken lines shown in FIGS. 1-9 illustrate portions of the armature cam that form no part of the claimed design.
